MILK BOTTLE WASHER

Jesse W. Fogg, Barrington, Ill., and Fred H. Fruhling, Little Falls, N. Y., assignors to Cherry-Burrell Corporation, Chicago, Ill., a corporation

Application March 24, 1937, Serial No. 132,786

27 Claims. (Cl. 141—7)

Our invention relates to that class of milk bottle washers, now in common use, in which the bottles to be washed are arranged in groups on appropriate carriers in endless conveyors normally traveling in uninterrupted order. Each group comprising a number of bottles side by side in line with each other transversely of the machine, and these groups of bottles are advanced in unbroken series through the machine, and at the point of delivery each group is discharged upon a conveyor leading to a bottle refilling machine. In a bottle washer of this class it is desirable that the clean bottles be delivered one complete group at a time at regular intervals so that a continuous series of said groups of bottles will be placed upon the delivery conveyor, resulting in a continuous supply of clean bottles equally spaced apart being fed to the refilling machine.

In the normal use of machines of this class, an operator visually inspects the bottles when placed upon the discharge conveyor by the machine, and the machines now in use are so arranged that the operator may, if he sees a bottle visibly unclean or otherwise objectionable, remove a single bottle by hand and replace with another bottle which may not be perfectly clean or sterilized.

The object of our invention is to provide an inspection compartment at the delivery point of a bottle washing machine, so constructed that the operator may remove objectionable or soiled bottles from the conveyor as soon as discharged by the washing machine but cannot replace these by other bottles and that all bottles delivered from the machine in its normal operation shall be untouched by the operator's hands, and otherwise sanitary, thereby avoiding the possibility of delivering to the refilling machine unclean or unsterile bottles, and further to avoid the possibility of an operator touching with his hands any bottle which passes through the machine in the normal operation thereof and all bottles which may be touched by an operator when the inspection compartment is opened must be removed from the discharge portion of the washing machine and cannot be replaced.

A further object is to provide means whereby the inspection operator, upon observing an unclean or otherwise objectionable bottle within the inspection compartment, may readily, quickly and easily remove an entire group of bottles and at the same time automatically stop the bottle washing machine and conveyor, so that when the group in which the objectionable bottle was observed has been removed and the machine again started, the supply of bottles delivered to and placed upon the discharge conveyor will be in a continuous arrangement and equally spaced apart; and further in this connection it

is our object to provide means whereby when the group of bottles has thus been removed and the door of the inspection compartment has been closed, the bottle washing machine and conveyor are automatically restarted.

A further object is to provide an inspection compartment of this character with simple and inexpensive means for preventing water of condensation therein from dropping upon the bottles.

In the accompanying drawings,

Figure 1 shows a side elevation partly in vertical central section illustrating a portion of a bottle washing and bottle conveying mechanism having applied thereto our improved inspection enclosure mechanism.

Figure 2 shows a front elevation, partly in section, taken on the line 2—2 of Figure 1.

Figure 3 shows an enlarged detail sectional view of the switch mechanism.

Figure 4 shows a side elevation of a portion of a bottle washing mechanism and our improved inspection enclosure mechanism illustrating the switch operating mechanism.

Figure 5 shows a vertical longitudinal sectional view illustrating a modified form of our inspection enclosure device.

Figure 6 shows a top or plan view of another modified form of our invention with the cover of the inspection enclosure removed.

Figure 7 shows a front elevation of the same modification illustrating the means for the removal of bottles from the conveyor, operatively connected with the door of the inspection enclosure.

Figure 8 shows a front end elevation of a bottle washing machine embodying our invention and illustrating an enclosed conveyor leading therefrom to a refilling machine or other delivery point; and

Figure 9 shows a sectional view on the line 9—9 of Figure 8.

Referring to the accompanying drawings the reference numeral 10 is used to indicate generally the body of the bottle washing machine and its internal conveyor. The conveying mechanism 10a within the washing machine is operatively connected with an electric motor 11, and certain spray elements in the washing mechanism are operatively connected with an electric motor and pump unit 12. There is also a conveyor enclosure 13a and a conveyor 13 for delivering washed bottles from the machine to a point distant, such, for instance, as a bottle refilling machine, indicated generally in Figure 8 by the reference symbol 13b. The conveyor 13 may be driven in any ordinary manner, such, for instance, as an electric motor, not shown. The structural details of the parts just described are not herein fully illustrated and described

but are simply shown as illustrative of one form at least of these bottle washing conveying and filling machines now in common use.

Our improvement may be defined as an attachment to or improvement in bottle washing machines of this character, and consists of an improved enclosure over the bottle discharge portion of the bottle washer and is indicated generally by the reference numeral 14, having at one

10 side a bottle delivery opening 15 through which bottles on the conveyor 13 may pass out of the inspection enclosure and into the conveyor enclosure 13a which, as is clearly shown in Figures 8 and 9, is enclosed so that bottles can be removed 15 therefrom only at the delivery end of the conveyor device. Reference herein to the delivery end of the conveyor 13 means the discharge end of the enclosed part thereof.

At the front of the enclosure is a hinged door

20 17 provided with a handle 18. This door is preferably made of glass or other transparent material, so that the inspection operator may at all times visually inspect the bottles contained within the enclosure, and to aid in this inspection a lamp 16 is provided within the enclosure. In Figure 1 the door is shown in its wide open position. Fixed to the door are two arms 19, extended downwardly from the position shown in Figure 1. These arms support the bottle engaging frame consisting of three rods 20, fixed at their ends to said arms 19. The arrangement of these parts is such that, when the door 17 is in its closed position the rods 20 will stand above the space through which bottles are delivered from the washer and above and at the side of the conveyor 13 opposite from the door opening, and when the door is opened the rods 20 will engage all of the bottles upon the conveyor 13 within the inspection enclosure and bodily move them to the position shown in Figure 1. A stationary platform 21 is provided to support the bottles in this position. When the door 17 is in the position shown in Figure 1 the operator may remove all of the bottles contained upon the platform 21 and the rods 20, and these bottles must be removed before the washing machine can again be operated, because if the bottles are not removed and the door closed, these bottles would lie in a horizontal position 40 across the conveyor 13 and prevent a new series of bottles from being placed in upright position upon the conveyor 13 by the automatic discharge mechanism of the bottle washing machine.

45 55 As will be seen in Figure 1 of the drawings, the lower one of the rods 20 is positioned somewhat in advance of the others, so that upon opening the door 17 it will first engage the bottles near the bottoms of the same, causing them to tilt back over against the other rods to thereby avoid the possibility of forcing the bottles from the compartment and breaking them. Furthermore, the upper rods 20 are so positioned that when the door 17 is open they will extend over 60 the conveyor 13 and thereby prevent the manual return of bottles to the conveyor 13.

65 70 For the purpose of preventing the removal by the conveyor 13 or replacing of bottles upon the conveyor 13 when the door 17 is opened, we have provided an extension 22 on one of the arms 19 adjacent the opening 15, in the enclosure 14, which arm is of such shape that, as shown in Figure 1, it forms a closure for the opening 15 when the door 17 is opened. This operates to 75 prevent any bottles being carried away by the

conveyor, as well as to prevent an operator reaching a bottle within the enclosure at the time the door is beginning its opening movement. However, when the door 17 is closed this closure stands in the rear of the opening 15 and does 5 not form a closure for said opening.

We have provided means whereby the opening and closing of the door 17 will properly control the operation of the bottle washing machine and its conveyors. For this purpose we have provided an electric switch, indicated generally by the reference numeral 23, shown in Figure 3, and which includes a spring actuated circuit closure 24 and a contact 25, and slidably mounted in this switch is the push rod 26, and when the push rod 26 is moved downwardly the circuit will be opened and when pressure is removed from it the circuit will be closed by the spring 24. The electric current controlled by this switch mechanism is led by conductors 27 to a 20 control box 28, and from this control box, mechanism not shown is provided for operatively connecting it with the motor and pump unit 12 of the washing machine. Another similar switch mechanism, indicated generally by the reference numeral 29 in Figure 4, is provided for controlling the motor 11 of the conveyor mechanism 10a of the washing machine.

For the purpose of opening and closing these two switches at the same time we have provided a pivoted lever 30, normally held upwardly in a substantially horizontal position by a spring 31 to which is attached a cam follower 32a and a switch actuating bar 32 which, when moved downwardly by lever 30, depresses the push rods 35 26 in both switches. For the purpose of automatically operating the switches to open them instantly when the door 17 is opened, we have provided on the door 17 a cam 33, shown in Figure 4, provided at its end adjacent the door 17 with a recess or notch 34 below the datum plane 33a of the cam shown in dotted lines, and a stop 35 at the other end of the cam above the datum plane thereof. Said cam is normally held in engagement with the cam follower 32a mounted on the lever 30. This cam structure is such that when the door is in the position shown in Figure 4, the switches are open and the door is held in position by the engagement of the follower 32a with the recess adjacent stop 35, and when the door is closed, the cam will permit the lever 30 to move upwardly when the cam follower 32a engages the recess 34 which is below the datum plane 33a of cam track 33, and thus close the switches. This switch mechanism actuated by 55 the cam also functions to automatically stop the motors of both the washing machine pumping unit 12 and the washing machine conveyor mechanism 10a when the door 17 is opened, and to automatically start both mechanisms when 60 the door 17 is closed.

In the bottle washing machines now in common use the bottles delivered to the conveyor 13 are not contained in any enclosure, but when our type of enclosure is applied or constitutes 65 part of the washer it becomes advisable to provide means for preventing water of condensation in the interior of the enclosure from coming in contact with the sterile washed bottles, and for this purpose we have provided a hood 36, immediately above the lamp 17, which hood is provided with a discharge pipe 37 leading to the exterior of the inspection enclosure. The heat from the lamp creates a current of air, passing 70 upwardly through the discharge pipe 37 carrying 75

with it such moisture within the inspection enclosure as might result in water of condensation.

In practical use with this form of our invention the operator, positioned at the inspection enclosure, may clearly see all of the bottles as they are delivered from the washer to the delivery conveyor 13. In the event that he observes any one of the series of bottles delivered at one time to the conveyor 13 is not clean, or is otherwise defective, or improperly positioned, then he at once opens the door 17. This automatically removes the entire series of bottles within the inspection enclosure, from the conveyor 13 and at the same time stops the entire washing procedure. The operator then removes all of the bottles thus discharged from the inspection enclosure. The operator is prevented from returning any of the bottles thus removed, to the conveyor 13, because of the rods 20 operatively connected with the door 17 at the front, and the closure 22 covering the opening 15, and the washing machine cannot again be started until the bottles have thus been removed and the door 17 closed. If the operator attempted to close the door 17 with the bottles resting on the rods 20, these bottles would be placed in horizontal position across the top of the conveyor 13, which in turn would prevent the bottle ejecting mechanism of the bottle washer from delivering bottles to the conveyor 13.

In Figure 5 we have shown a modified form of our invention which differs from the form illustrated in Figures 1 to 4, inclusive, primarily in that when the door 17 is opened, the bottles contained upon that portion of the conveyor 13 which is within the inspection enclosure, instead of being withdrawn outwardly through the front of the inspection enclosure by the rod 41, they are pushed back upon the discharge mechanism 40 of the washing machine and thereby serve as obstructions to prevent further operation of the bottle washing machine without breaking bottles. In this form of the invention a bell crank lever 38 is pivoted to the door 17 and a lever 39 is pivoted 45 to a part of the inspection enclosure, and these two levers are pivotally connected at 40. A similar arrangement of levers 38 and 39 is provided at each side of the door opening. A rod 41 is extended across the inspection enclosure from one of the levers 39 to the other. When the door 17 is closed this rod 41 stands in the position shown by dotted lines at 42, and when the door is opened this rod 41 moves across the top of the conveyor 13 and pushes the bottles backwardly 50 upon the discharge mechanism of the bottle washing machine.

In this modified form we have also shown an electric switch mechanism for shutting off the motors 11 and 12 for the washing and conveying mechanisms when the door is opened and which comprises a switch device, indicated generally by the reference numeral 43, and a switch closing arm 44 fixed to the lever 38, and these parts are so arranged that when the door 17 is in the position shown by solid lines in Figure 5, the switch mechanism 43 is opened, and when moved to the position shown by dotted lines, the switch 43 is closed.

Another modification of our invention is illustrated in Figures 6 and 7, in which there is disclosed a means for automatically diverting the bottles from the conveyor 13 immediately after the bottles come out of the inspection enclosure. This mechanism comprises a pivoted arm 45 fixedly mounted just above the rear edge of the

conveyor 13 at the point where the conveyor passes out of the inspection enclosure through the opening 15. Fixed to the arm 45 is a short arm 45a below the conveyor, and this arm 45a is connected by a link 46, shown by dotted lines 5 in Figure 6, with another similar lever 47 on the opposite side of the conveyor 13. This lever 47 is fixed to an upright shaft 48, to the upper end of which is fixed a beveled pinion 49 enmeshed with a beveled pinion 50 on the hinge rod 51 10 fixed to the door 17 of the inspection enclosure. Said link 46 is permitted to travel through a slot 46a in the table 52. Adjacent the outer ends of the arms 45 and 47 is a table 52 to receive the milk bottles thus diverted by said arms from 15 the conveyor 13. In this modified form of the invention means are also provided for controlling the motors 11 and 12 of the washing machine and its conveying mechanisms 10a, by means of an electric switch, indicated generally by the 20 reference numeral 53 and operated by an arm 54 connected with the arm 45, the arrangement being such that when the arms 45 and 47 are in the position shown by solid lines in Figure 6, the switch is open and the motors for the bottle 25 washing mechanism and the conveyor 10a are stopped. However, the conveyor 13 may continue to operate, and when these arms 45 and 47 are returned to the position shown by dotted lines in Figure 6, the switch mechanism is closed and 30 the washing machine mechanism is operated.

In practical use our invention is combined with a conveyor 13 enclosed by a cover 13a thereby insuring the passing of sterile bottles from the washer to a filler 13b, and it is obvious that our 35 invention does not in any way interfere with the normal operation of the bottle washing machinery, nor does it interfere in any way with the normal inspection of the bottles by the operator. When the operator, however, sees a bottle which 40 is not clean or which is otherwise defective or misplaced, all that is necessary is for him to open the door 17 and thereby remove all of the bottles within the inspection enclosure. During 45 the time that this door is open, however, the operator is prevented from putting bottles upon the delivery conveyor within the inspection enclosure, with the result that all of the bottles that have been delivered from the machine to a refilling mechanism or the like, are bottles that have gone 50 through the washing, rinsing and sterilizing operations of these bottle washing machines and have not been manually handled subsequent to the sterilizing operation. When a bottle washer 55 is provided with our improved discharge enclosure from which the clean bottles are fed into a conveyor in which the bottles are not accessible to handling, it will be impossible for the operator of the washing machine to handle the bottles discharged by the washer before they reach the 60 bottle refilling mechanism as illustrated in Figure 8 unless they are completely removed from the enclosed discharge by means of the removing door provided therefor.

We claim as our invention:

1. In a machine of the class described, the combination of a conveyor designed to receive bottles and deliver them to a point of discharge, an inspection enclosure through which said bottles may be visually inspected, said enclosure having an opening through which bottles on said conveyor may be discharged from the enclosure, and being otherwise sufficiently enclosed to prevent the removal of bottles, a door for said enclosure, means operatively connected with the door for 75

removing the bottles from the conveyor upon the opening of the door, and means operatively connected with the door for closing said opening in the enclosure when the said door is open.

- 5 2. In a machine of the class described, the combination of a conveyor designed to receive bottles and deliver them to a point of discharge, an inspection enclosure through which said bottles may be visually inspected, said enclosure having an opening through which bottles on said conveyor may be discharged from the enclosure, and being otherwise sufficiently enclosed to prevent the removal of bottles, a door at one side of the enclosure adjacent one side of the conveyor, 10 and a bottle engaging structure carried by the door and positioned when the door is closed on the side of the conveyor opposite the door and whereby when the door is opened said bottle engaging structure will engage bottles on the conveyor and remove them outwardly through the door opening.

- 15 3. In a machine of the class described, the combination of a conveyor designed to receive bottles and deliver them to a point of discharge, 20 an inspection enclosure through which said bottles may be visually inspected, said enclosure having an opening through which bottles on said conveyor may be discharged from the enclosure, and being otherwise sufficiently enclosed to prevent the removal of bottles, a door at one side of the enclosure adjacent one side of the conveyor, 25 a bottle engaging structure carried by the door and positioned when the door is closed on the side of the conveyor opposite the door and whereby 30 when the door is opened said bottle engaging structure will engage bottles on the conveyor and remove them outwardly through the door opening, and a closure device operatively connected with said door positioned when the door is open to 35 close the opening in the enclosure through which the conveyor extends and positioned when the door is closed to uncover said opening.

- 40 4. In a machine of the class described, the combination of a conveyor designed to receive bottles and deliver them to a point of discharge, an inspection enclosure through which said bottles may be visually inspected, said enclosure having an opening through which bottles on said conveyor may be discharged from the enclosure, and being otherwise sufficiently enclosed to prevent the removal of bottles, a door at one side of the enclosure adjacent one side of the conveyor, a bottle engaging structure carried by the door and positioned when the door is closed on the side 45 of the conveyor opposite the door and whereby when the door is opened said bottle engaging structure will engage bottles on the conveyor and remove them outwardly through the door opening, and a stationary platform for supporting bottles removed from the conveyor upon the opening of said door.

- 50 5. In a machine of the class described, the combination of a conveyor designed to receive bottles and deliver them to a point of discharge, 55 an inspection enclosure through which said bottles may be visually inspected, said enclosure having an opening through which bottles on said conveyor may be discharged from the enclosure, and being otherwise sufficiently enclosed to prevent the removal of bottles, manually operable means for removing from the enclosure the bottles contained on the conveyor within the enclosure, means on the interior of the enclosure for lighting it and thereby creating heat, and means for conducting the heated air to a point

of discharge to thereby prevent the accumulation of water of condensation within the enclosure.

6. The combination with a bottle washing machine having a delivery conveyor and motor operated means for placing bottles thereon and for operating the conveyor, of an inspection enclosure for that part of said conveyor upon which bottles are placed by the bottle washing machine, said enclosure being formed with an opening through which bottles on said conveyor may be removed, and being otherwise sufficiently enclosed to prevent the removal of bottles, and manually operable means which in one position permits the movement of the conveyor to deliver bottles from the enclosure through said opening to a point distant from the enclosure and which in another position automatically prevents the bottles contained in the enclosure at the time said means is manually operated from being delivered by the conveyor to said distant point.

7. The combination with a bottle washing machine having a delivery conveyor and motor operated means for placing bottles thereon, of an inspection enclosure for that part of said conveyor upon which bottles are placed by said motor operated means, said enclosure being formed with an opening through which bottles on said conveyor may be removed, and being otherwise sufficiently enclosed to prevent the removal of bottles, a door for said enclosure, means mechanically operated for removing from the conveyor the bottles thereon when the door is opened, and a switch mechanism operatively connected with the door for stopping said motor operated means when the door is opened.

8. The combination with a bottle washing machine having a delivery conveyor and motor operated means for placing bottles thereon, of an inspection enclosure for that part of said conveyor upon which bottles are placed by said motor operated means, said enclosure being formed with an opening through which bottles on said conveyor may be removed, and being otherwise sufficiently enclosed to permit the removal of bottles, a door for said enclosure, means mechanically operated for removing from the conveyor the bottles thereon when the door is opened, and a switch mechanism operatively connected with the door for stopping said motor operated means when the door is opened, said door and switch mechanism also including means for starting said motor operated means when said door is moved to closed position.

9. The combination with a bottle washing machine having a delivery conveyor and motor operated means for placing bottles thereon, of an inspection enclosure for that part of said conveyor upon which bottles are placed by said motor operated means, said enclosure being formed with an opening through which bottles on said conveyor may be removed, and being otherwise sufficiently enclosed to prevent the removal of bottles, a door for said enclosure, means mechanically operated for removing from the conveyor the bottles thereon when the door is opened, a switch mechanism operatively connected with the door for stopping said motor operated means when the door is opened, and a closure for said opening in the enclosure operatively connected with said door and movable to position to close said opening when said door is open.

10. The combination with a bottle washing machine having a delivery conveyor and motor operated means for placing bottles thereon, of an

- inspection enclosure for that part of said conveyor upon which bottles are placed by said motor operated means, said enclosure being formed with an opening through which bottles on said conveyor may be removed, and being otherwise sufficiently enclosed to prevent the removal of bottles, a door for said enclosure, means mechanically operated for removing from the conveyor the bottles thereon when the door is opened, a switch mechanism operatively connected with the door for stopping said motor operated means when the door is opened, a closure for said opening in the enclosure operatively connected with said door and movable to position to close said opening when said door is open, motor operated mechanism for bottle washing, and a second switch operatively connected to said door for stopping the motor of the motor operated mechanism for bottle washing when the door is opened.
11. The combination with a bottle washing machine having a delivery conveyor and motor operated means for placing bottles thereon, of an inspection enclosure for that part of said conveyor upon which bottles are placed by the motor operated means, said enclosure being formed with an opening through which bottles on said conveyor may be removed, and being otherwise sufficiently enclosed to prevent the removal of bottles, a door for said enclosure, means mechanically operated for removing from the conveyor the bottles thereon when the door is opened, a switch mechanism operatively connected with the door for stopping the motor operated means when the door is opened, a closure for said opening in the enclosure operatively connected with said door and movable to position to close said opening when said door is open, motor operated mechanism for bottle washing, and a second switch operatively connected to said door for stopping the motor operated mechanism for bottle washing when the door is opened, said switch mechanism including a cam carried by the door and a spring actuated switch opening and closing member operated by said cam.
12. In a bottle washing machine, the combination of a combined delivery and inspection compartment for washed bottles, said compartment being fully enclosed to the extent that an operator cannot touch the bottles thereon, a conveyor within said compartment leading to a distant point and also fully enclosed to prevent handling of the bottles therein, means whereby said delivery and inspection compartment may be opened for the removal of bottles therefrom, and means whereby manual replacement of bottles in upright positions on the conveyor in said compartment, when thus opened, is prevented.
13. In a bottle washing machine, the combination of a combined delivery and inspection compartment for washed bottles, said compartment being fully enclosed to the extent that an operator cannot touch the bottles thereon, a conveyor within said compartment leading to a distant point and also fully enclosed to prevent handling of the bottles therein, means whereby said delivery and inspection compartment may be opened for the removal of bottles therefrom, and means automatically operated upon the opening of said compartment whereby manual replacement of bottles in said compartment, when thus opened, is prevented.
14. In a machine of the class described, the combination of a conveyor designed to receive bottles and deliver them to a point of discharge, an inspection enclosure through which said bot-
- ties may be visually inspected, said enclosure having an opening through which bottles on said conveyor may be discharged from the enclosure, and being otherwise sufficiently enclosed to prevent the removal of bottles, a door for said enclosure, and means operatively connected with the door for removing the bottles from the conveyor upon the opening of the door, said means being so shaped and positioned that when the door is opened they will prevent manual replacement of bottles on the conveyor through the door opening.
15. In a machine of the class described, the combination of a conveyor designed to receive bottles and deliver them to a point of discharge, an inspection enclosure through which said bottles may be visually inspected, said enclosure having an opening through which bottles on said conveyor may be discharged from the enclosure, and being otherwise sufficiently enclosed to prevent the removal of bottles, a door for said enclosure, and means operatively connected with the door for preventing the replacement of bottles upon the conveyor through the door opening when the door is in its open position.
16. In combination, mechanism for washing bottles having bottle discharging mechanism for discharging them onto a conveyor, conveying means for moving said washed bottles to a bottle filling mechanism, an inspection enclosure having a transparent door adjacent that part of said conveyor upon which bottles are placed by the discharging mechanism, said enclosure being formed with an opening through which bottles on said conveyor may pass, and being otherwise sufficiently enclosed to prevent the handling of bottles in the enclosure, and means operatively associated with said enclosure for preventing the insertion of bottles upon the conveyor when said door is open.
17. In combination, mechanism for washing bottles having bottle discharging mechanism for discharging them onto an enclosed conveyor, conveying means for moving said washed bottles to a bottle filling mechanism, an inspection enclosure for that part of said conveyor upon which bottles are placed by the discharging mechanism, said enclosure being formed with an opening through which bottles on said conveyor may pass, said enclosure and conveyor and washing machine being otherwise sufficiently enclosed to prevent the handling of bottles during their passage through the series of mechanisms, a door for said enclosure, and means operatively associated with said door for obstructing said opening when said door is open.
18. In combination, mechanism for moving bottles through a bottle washer, mechanism for discharging the washed bottles from said moving mechanism and placing them on a conveyor, conveying means for moving said washed bottles to a bottle filling mechanism, an inspection enclosure for said discharge mechanism and that part of the conveyor upon which the bottles are placed when being discharged from the washer, said enclosure being formed with an opening through which bottles on said conveyor may pass, and being otherwise sufficiently enclosed to prevent the handling of bottles in the enclosure, a door for said enclosure, and means operatively connected with the door for removing the bottles from the conveyor upon the opening of the door.
19. In a bottle washing machine having discharge mechanism for delivering bottles to a

- conveyor, the combination of a conveyor for washed bottles extending from a bottle loading point to a bottle delivery point, a bottle inspection compartment through which said conveyor moves and which is enclosed to prevent the removal of bottles except by said conveyor and which permits the visual inspection of bottles moving through it, and means capable of manual operation by an inspector for moving selected bottles upon the portion of the conveyor within the inspection compartment to positions where they will not be carried by the conveyor from within the inspection compartment to the delivery point of the conveyor, said means being so constructed and arranged whereby, upon the removal of selected bottles from the conveyor, the manual replacement of the bottles upon the conveyor is prevented.
20. In a bottle washing machine having discharge mechanism for delivering bottles to a conveyor the combination of a conveyor for washed bottles extending from a bottle loading point to a bottle delivery point, a bottle inspection compartment through which said conveyor moves and which is enclosed to prevent the removal of bottles except by said conveyor and which permits the visual inspection of bottles moving through it, and means capable of manual operation for removing from said conveyor bottles selected while within said inspection compartment before said selected bottles are delivered to said bottle delivery point by said conveyor moving through said inspection compartment, said means being so constructed and arranged whereby, upon the removal of selected bottles from the conveyor, the manual replacement of the bottles upon the conveyor is prevented.
25. In a bottle washing machine having discharge mechanism for delivering bottles to a conveyor, the combination of a conveyor for washed bottles extending from a bottle loading point to a bottle delivery point, a bottle inspection compartment through which said conveyor moves and which is enclosed to prevent the removal of bottles except by said conveyor and which permits the visual inspection of bottles moving through it, and means capable of manual operation by an inspector for moving selected bottles upon the conveyor and within the inspection compartment laterally away from the conveyor, said means being so constructed and arranged whereby, upon the removal of selected bottles from the conveyor, the manual replacement of the bottles upon the conveyor is prevented.
30. In a bottle washing machine, the combination of a conveyor for washed bottles extending from a bottle loading point to a bottle delivery point, a bottle inspection compartment through which said conveyor moves and which is enclosed to prevent the removal of bottles except by said conveyor and which permits the visual inspection of bottles moving through it, and means capable of manual operation by an inspector for moving selected bottles upon the conveyor through said door opening at one side of the conveyor device, a movable door for said opening, and means operated upon the opening of the door for removing bottles laterally from the conveyor through said door opening.
35. In a bottle washing machine, the combination of a conveyor for washed bottles extending from a bottle loading point to a bottle delivery point, a bottle inspection compartment through which said conveyor moves and which is enclosed to prevent the removal of bottles except by said conveyor and which permits the visual inspection of bottles moving through it, and means capable of manual operation by an inspector for moving selected bottles upon the conveyor through said door opening at one side of the conveyor device, a movable door for said opening, and means operated upon the opening of the door for removing bottles laterally from the conveyor through said door opening.
40. In a bottle washing machine, the combination of a conveyor for washed bottles extending from a bottle loading point to a bottle delivery point, a bottle inspection compartment through which said conveyor moves and which is enclosed to prevent the removal of bottles except by said conveyor and which permits the visual inspection of bottles moving through it, and means capable of manual operation by an inspector for moving selected bottles upon the conveyor through said door opening at one side of the conveyor device, a movable door for said opening, and means operated upon the opening of the door for removing bottles laterally from the conveyor through said door opening.
45. In a bottle washing machine, the combination of a conveyor for washed bottles extending from a bottle loading point to a bottle delivery point, a bottle inspection compartment through which said conveyor moves and which is enclosed to prevent the removal of bottles except by said conveyor and which permits the visual inspection of bottles moving through it, and means capable of manual operation by an inspector for moving selected bottles upon the conveyor through said door opening at one side of the conveyor device, a movable door for said opening, and means operated upon the opening of the door for removing bottles laterally from the conveyor through said door opening.
50. In a bottle washing machine, the combination of a conveyor for washed bottles extending from a bottle loading point to a bottle delivery point, a bottle inspection compartment through which said conveyor moves and which is enclosed to prevent the removal of bottles except by said conveyor and which permits the visual inspection of bottles moving through it, and means capable of manual operation by an inspector for moving selected bottles upon the conveyor through said door opening at one side of the conveyor device, a movable door for said opening, and means operated upon the opening of the door for removing bottles laterally from the conveyor through said door opening.
55. In a bottle washing machine, the combination of a conveyor for washed bottles extending from a bottle loading point to a bottle delivery point, a bottle inspection compartment through which said conveyor moves and which is enclosed to prevent the removal of bottles except by said conveyor and which permits the visual inspection of bottles moving through it, and means capable of manual operation by an inspector for moving selected bottles upon the conveyor through said door opening at one side of the conveyor device, a movable door for said opening, and means operated upon the opening of the door for removing bottles laterally from the conveyor through said door opening.
60. In a machine of the class described, the combination of a conveyor constructed and arranged to receive bottles and deliver them to a point of discharge, an inspection enclosure through which said bottles may be visually inspected, said enclosure having an opening through which bottles on said conveyor may be discharged from the enclosure and being otherwise sufficiently enclosed to prevent the removal of bottles, a door for said enclosure, and means operatively connected with the door for removing the bottles from the conveyor upon the opening of the door.
65. In a machine of the class described, the combination of a conveyor constructed and arranged to receive bottles and deliver them to a point of discharge, an inspection enclosure through which said bottles may be visually inspected, said enclosure having an opening through which bottles on said conveyor may be discharged from the enclosure and being otherwise sufficiently enclosed to prevent the removal of bottles, a door for said enclosure, and means operatively connected with the door for removing the bottles from the conveyor upon the opening of the door.
70. In a machine of the class described, the combination of a conveyor constructed and arranged to receive bottles and deliver them to a point of discharge, an inspection enclosure through which said bottles may be visually inspected, said enclosure having an opening through which bottles on said conveyor may be discharged from the enclosure and being otherwise sufficiently enclosed to prevent the removal of bottles, a door for said enclosure, and means operatively connected with the door for removing the bottles from the conveyor upon the opening of the door.

CERTIFICATE OF CORRECTION.

Patent No. 2,196,389.

April 9, 1940.

JESSE W. FOGG, ET AL.

It is hereby certified that error appears in the printed specification of the above numbered patent requiring correction as follows: Page 4, second column, line 45, claim 8, for the word "permit" read --prevent--; line 55-56, claim 9, for "machaine" read --machine--; page 6, first column, line 21, claim 20, after "conveyor" first occurrence, insert a comma; and second column, line 32, claim 25, for "mechine" read --machine--; and that the said Letters Patent should be read with this correction therein that the same may conform to the record of the case in the Patent Office.

Signed and sealed this 29th day of October, A. D. 1940.

Henry Van Arsdale,

Acting Commissioner of Patents.
